AUTOMATIC TRAIN STOP SYSTEM FOR
RAILROADS

Thomas Kittredge, Rutherford, N. J., and Herbert D. Brooks, Oceanside, N. Y., assignors to General Railway Signal Company, Rochester, N. Y.

Application February 17, 1934, Serial No. 711,700

4 Claims. (Cl. 246—47)

This invention relates to automatic train stop systems for railroads, and more particularly to the control circuits for the train stop or trip devices on the track commonly employed in such 5 systems on subways and the like.

One object of this invention is to provide an improved organization of relays and control circuits for electrically controlled trip stops, which will allow the clearing of the trip upon the entrance of a train into the associated track section 10 after a time interval determined by the sequential operation of the home and distant relays commonly employed, in such a way that a longer time interval may be obtained with the number 15 of relays ordinarily used than is possible at present.

Other objects, characteristic features, and advantages of the invention will be in part apparent, and in part pointed out as the description 20 progresses.

The accompanying drawings show in a simplified and diagrammatic manner one embodiment of the invention as applied to one control location, Fig. 1 showing the parts and circuits in the 25 normal condition with no trains present, and Fig. 2 showing the parts and circuits when the train stop is in the raised or stop position, due to the presence of a train ahead.

In the embodiment of the invention illustrated, 30 it is assumed that the trackway is divided into blocks such as A and B in the usual manner; that signals of a suitable type, such as color-light signals S, are located at the entrance to each block and controlled in accordance with the usual practice; and that a suitable form of trip stop, designated V and shown conventionally, will be located near the entrance to each block, a predetermined distance in advance of the insulated 35 joints, this trip stop being of the well-known type comprising electrically controlled power mechanism for moving the trip arm from its raised or 40 stopping position to a clear position against a spring or counter-weight, as 38, and maintained there. In the form illustrated, this trip stop mechanism is assumed to be operated to the clear 45 position by an electric motor M, through gearing or the like 40, and held in that position by a hold-clear device W coacting with an armature 41 on the device V. This trip stop mechanism also 50 includes a circuit controller, arranged to open and close contacts in different positions. This circuit controller is illustrated diagrammatically as comprising pivoted contact arms 1 to 5, movable through an angle of 90°, and engaging arcuate 55 segments or stationary contacts in different positions of the trip arm.

The usual track relay T, home relay HR, and distant relay DR, commonly used in systems of this type, are shown diagrammatically and conventionally. The home and distant relays are

assumed to be of the two-element alternating current type, with local and line phase windings. Such relays operate their contacts only when both windings are energized.

For the purpose of simplifying the drawings, 5 the conventional symbols BX, NX, and CX are employed to indicate connections to a transformer supplying current to the various circuits, it being understood that BX and NX indicate terminals having positive and negative instantaneous volt- 10 age in relation to the terminal CX.

Fig. 1 illustrates the parts in the normal condition with no trains present. The track relays T and 1T of the blocks or track sections A and B are both energized. The line phase winding H of 15 the line relay HR is energized by a circuit readily traced from BX 55, through the front contact 6 of track relay 1T, line wire 7, front contact 8 of track relay T, wires 9 and 10, winding H, to CX. The local winding HQ of this relay is energized 20 over the same line circuit through wire 11, front contact 12 of relay HR, wires 13 and 14, winding HQ, to CX.

The local winding DQ of the distant relay DR 25 is directly energized; and the line phase winding D is energized over the line circuit from NX 55, through front contact 15 of the line relay 1HR for the block B, line wire 16, front contact 17 of track relay T, wire 18, winding D, to CX.

The train stop V is held in the clear position 30 by the energization of hold-clear W over a circuit from BX 110, front contact 20 of track relay T, wires 21 and 22, front contact 23 of line relay HR, wires 24 and 25, circuit controller contact 3 of the stop mechanism, closed in the clear position, wire 26, hold-clear W, to NX 110. 35

Thus, under normal clear conditions, with no train present, the line relay HR and the distant relay DR are both energized; and the train stop V is held in the clear position. 40

When a train enters block A under such clear conditions, the dropping of the track relay T establishes a retaining circuit for holding the trip stop in the clear position, said circuit being from BX 110, back contact 28 of track relay T, wire 45 27, circuit controller contact 4 closed in the clear position, wires 28 and 26, hold clear W, to NX 110.

Considering now the case where there is a train ahead in the block B, as shown in Fig. 2, the presence of this train drops the track relay 1T, 50 opening its front contacts 6 and 8 to de-energize the line relays HR and 1HR. The opening of the front contact 15 of the line relay 1HR de-energizes the distant relay DR. Thus, the signal S indicates stop, there being the usual one block overlap characteristic of the trip stop system. The de-energization of the line relay HR opens its front contact 23 and thus de-energizes the hold clear W, so that the trip stop V assumes 55 its stopping position. 60

In accordance with this invention, a train may pass the stop signal S and enter the block A, without being tripped or automatically stopped, provided it is travelling at a very low speed. This result is obtained by locating the trip stop V a short distance in advance of the insulated joints, so that the train may travel a short distance, after dropping the track relay T, before encountering the trip stop, and by providing circuits for clearing the trip stop after a short interval of time, so that if the train consumes more than a predetermined time in travelling such predetermined distance, corresponding with a speed below the desired speed limit, the trip stop will be clear by the time the train reaches it. This time interval is measured in accordance with this invention by the sequential operation of the home and distant relays.

Assume now that a train enters the block A under danger traffic conditions with a train ahead in the block B, as shown in Fig. 2. The dropping of the track relay T closes a circuit for energizing the distant relay DR, which may be traced from BX 55, circuit controller contact 1 of the trip stop closed in the stop position, wires 30 and 13, back contact 12 of the line relay HR, wire 31, back contact 17 of track relay T, wire 18, winding D to CX. This energization of the distant relay DR establishes a circuit for energizing the line phase winding H of the home relay HR from BX 110, back contact 20 of track relay T, wires 27 and 32, circuit controller contact 5 of the trip stop mechanism closed in the stop position, wire 33, front contact 34 of relay DR, wires 35 and 10, winding H, to CX. The local winding HQ of the home relay HR is directly energized through the circuit controller contact 1 of the stop mechanism.

When the home relay HR is thus energized, the closing of its front contact 12 provides a circuit for energizing its line phase winding H through the circuit controller contact 1. Also, the opening of the back contact 12 of the home relay HR de-energizes the distant relay DR, which closes its back contact 36, so that a circuit for the motor M of the train stop mechanism is established from BX 110, through the back contact 36 of relay DR, wires 37 and 22, front contact 23 of relay HR, wire 24, circuit controller contact 2 of the trip stop mechanism, wire 39, motor M, to NX 118.

The trip stop mechanism now operates to the clear position, the circuit controller contacts 1 and 2 remaining closed until the trip arm reaches the clear position and circuit controller contacts 3 and 4 are closed, whereupon the opening of contact 1 de-energizes the home relay HR, the opening of contact 2 de-energizes the motor M, and the closing of contact 4 establishes the retaining circuit through the back contact 20 of the track relay T to hold the trip in the clear position.

It will be noted that the time interval between the dropping of the track relay T and the movement of the trip stop V to the clear position is measured by time intervals required to energize distant relay DR, then energize the home relay HR, then de-energize distant relay DR, then move the trip arm to the clear position. In other words, in addition to the usual clearing time of the trip stop mechanism, the organization of

control circuits in accordance with this invention requires the sequential picking up of the distant and home relays, followed by the dropping of the distant relay, thereby providing an additional time interval from the same relays commonly employed. 5

Various adaptations, additions, and modifications, may be made in the particular construction and arrangement of parts shown and described, without departing from the invention. 10

What we claim is:—

1. In an automatic stop system for railroads, in combination, an electrically controlled stop mechanism located a short distance beyond the entrance to a block having the usual track relay, 15 a home relay and a distant relay, a clearing circuit for said stop mechanism including a front contact of the home relay and a back contact of the distant relay, and circuit means controlled by said track relay for picking up the distant relay and home relay in succession, and then dropping the distant relay to establish said clearing circuit.

2. In an automatic train stop system of the character described, a trip stop mechanism, a 25 track relay, a home relay, and a distant relay, means controlled by said track relay and effective when the track relay is deenergized and the stop mechanism is in the stopping condition, to pick up the distant relay through a circuit controlled 30 by the home relay for actuating said stop mechanism to the clear position, after a time interval measured by the picking up of the distant relay and home relay in succession, and the dropping of the distant relay. 35

3. An automatic train stop for railroads, comprising, in combination, an electrically controlled stop mechanism located in a block, a track relay for said block, a home relay and a distant relay 40 for said block, and circuit means controlled by the said relays for clearing the stop mechanism, when the block next in advance is occupied, a predetermined time after the track relay has been shunted by occupancy of the said block, the circuit means including an energizing circuit for the 45 distant relay including a back point of the home relay and a back point of the track relay, and an energizing circuit for the home relay including a front point of the distant relay.

4. An automatic train stop for railroads, comprising, in combination, an electrically controlled stop mechanism located in a block, a track relay for said block, a home relay and a distant relay 50 for said block, and circuit means controlled by the said relays for clearing the stop mechanism, 55 when the block in advance is occupied, a predetermined time after the track relay has been shunted by occupancy of the said block, the circuit means including an energizing circuit for the distant relay including a back point of the 60 home relay and a back point of the track relay, and an energizing circuit for the home relay including a front point of the distant relay, and a control circuit for the stop mechanism requiring the distant relay down and the home relay up, 65 to thereby insert a predetermined time interval between release of the track relay and operation of the stop mechanism.
